THREE-WHEEL VEHICLE

Jerry P. Hepp and Glenn R. Thomas, both of
215 W. Central, Fairview, Okla. 73737

Filed June 25, 1973, Ser. No. 373,538

Term of patent 14 years

Int. Cl. D12—11

U.S. Cl. D12—107

FIG. 2

FIG. 1

FIG. 3

FIG. 4

FIG. 5

FIG. 1 is a side elevational view of a three-wheel vehicle showing our new design, the side opposite being a mirror image thereof;

FIG. 2 is a top plan view of FIG. 1;

FIG. 3 is a left end elevational view of FIG. 1;

FIG. 4 is a right end elevational view of FIG. 1; and

FIG. 5 is a bottom plan view of FIG. 1.

The dotted line representation of seats, pedals and controls shown in FIGS. 1 to 4 are for the purpose of illustration only.

We claim:

The ornamental design for a three-wheel vehicle, substantially as shown and described.
